RADIO RECEIVER SEQUENCE TUNER

Albert Blain, Philadelphia, Pa., assignor to Radio Corporation of America, a corporation of Delaware

Application April 24, 1946, Serial No. 664,475

14 Claims. (Cl. 74—10)

1

The present invention relates generally to automatic tuning mechanism for radio receivers, and more particularly to an automatic tuner of the sequence type in which a series of predetermined broadcasting stations to which the tuner is adjustably set in advance are successively and automatically tuned-in by actuation of a single control switch.

One of the objects of the invention is to provide a relatively simple, compact tuner of the type above mentioned which, although not limited thereto, is capable of use in automobile receivers because of its compactness and also because its source of operating energy may be the car battery or other low-voltage source.

A further object of the invention is to provide a rotatable turret of novel design which serves as the position-determining mechanism for the receiver tuning elements, and novel means for effecting a step-by-step rotation of the turret during each cycle of operation of the tuner.

A still further object of the invention is to provide a manually-operated device in conjunction with the turret which is adapted to serve both as a manual tuning means for the receiver and as the adjusting means for setting-up in advance the broadcasting stations desired to be automatically tuned-in.

These and other objects of the invention and the various features and details of the construction and operation thereof are hereinafter fully set forth and described and shown in the accompanying drawings, in which:

Fig. 1 is a plan view, partly broken away, of the tuner according to the invention;

Fig. 2 is a view, in front elevation, of the tuner shown in Fig. 1;

Fig. 3 is a bottom view of Fig. 1;

Fig. 4 is a view, in cross-section and on an enlarged scale, of the turret assembly;

Fig. 5 is an end view of Fig. 4 looking from the right in Fig. 4;

Fig. 6 is a cross-sectional view taken on the line VI—VI in Fig. 4;

Figs. 7A and 7B are plan views of the cam-slot used to explain the manner in which the step-by-step rotation of the turret is obtained;

Fig. 8 is a cross-sectional view, taken on the line VIII—VIII in Fig. 2, showing the relative arrangement of such parts, as the actuating solenoid, core-carriage bracket and turret assembly, at the beginning of a cycle of operation, and showing also the turret in the manual tuning position;

Fig. 9 is a view similar to Fig. 8 showing the mechanism at a point in the cycle of operation at

which the turret and the core assembly are at their respective limits of travel in the rearward direction;

Fig. 10 is an end view, partly in section, of the solenoid frame assembly, the section being taken on the line X—X of Fig. 8;

Figs. 11 and 12 are views of only the right-hand end of the core-carriage, Fig. 11 being a plan view and Fig. 12 being a view in front elevation; and

Fig. 13 is a view in cross-section and on an enlarged scale, of the manual tuning device.

Briefly, the sequence tuning mechanism of the invention consists of a slidable carriage to which the tuning element (or elements) of a radio receiver is attached, a multi-position rotatable turret provided with a plurality of axially-adjustable stops, one for each turret position, and actuating mechanism which, upon each operation thereof, actuates the tuning-element carriage and the turret in timed relation so that first the carriage is withdrawn from the turret-stop which was effective at a previous tuning-in operation, after which the turret is stepped to the next angular position to bring the stop corresponding thereto into operative position, and thereafter the carriage is returned to abut against said latter stop, whereat the tuning element (or elements) is adjustably set to tune the receiver to a new predetermined carrier-frequency.

According to the present embodiment the turret is capable of angular adjustment to six positions, five of which are utilized to automatically tune the receiver to predetermined carrier-frequencies assigned to the stations which are most frequently heard, and the sixth position is utilized to effect tuning of the receiver through its entire range by means of a manual tuning control member arranged to cooperate with the turret-stop corresponding to said sixth turret position. A solenoid under control of a manually-operated switch is the actuating means for causing, with the aid of a specially shaped cam-slot, rotation of the turret to successive positions of angular adjustment.

For a detailed description of the tuning mechanism and its manner of operation, reference will now be made to the drawings.

Referring first to Figs. 1, 2 and 3, there is shown at 1 a main plate support or frame member provided at the left and at the rear, respectively, with brackets 2 and 3 for attachment to the receiver chassis or other suitable fixed part of the receiver. The frame 1 is provided at its front edge with an integral depending plate 4, and aligned therewith, at the rear of the frame member, is affixed a

3
 bracket 6. Extending between front plate 4 and rear bracket 5 and journaled respectively in aligned holes 6 and 7 formed therein is a shaft 8 on which a core carriage, shown generally at 9, is adapted to slide. A second shaft 10 disposed in parallel to shaft 8 has its forward end journaled in a bushing 11 carried by the front plate 4 and its rear end journaled in a hole 12 formed in rear bracket 5. The shaft 10 at its forward end carries a turret, shown generally at 13, and both the shaft and turret are capable of limited axial movement for a purpose hereinafter to be described.

The tuning element of the receiver, shown here as of the type known as a permeability tuner, comprises a plurality of tuning coils (not shown), each housed in a shield can 14, and a plurality of magnetic cores 15, each movable within its respective coil, the axial adjustment of the cores with respect to their coils determining the tuning adjustment of the receiver. The several shield cans 14 are suitably supported on a depending bracket 16 fastened to frame 1 at its rear edge, said bracket 16 also supporting a number of trimmer condensers 17 on tabs 18 extending at right angles from the main body of bracket 16.

The core carriage 9, previously mentioned, is provided with a transverse member 19 to which the magnetic tuning cores 15 are attached through the medium of connecting wires 20 and adjusting screws 21 (Fig. 3). The transverse carriage member 19 is provided at the right (Figs. 1 and 3) with a bracket 22 which is mounted for sliding movement on shaft 8, and said member 19 is provided at the left (Fig. 2) with a slit or groove 23 which is adapted to receive a ledge 24 of a bracket 25 affixed to the underside of frame member 1, the ledge 24 and shaft 8 serving as a pair of rails on which the core supporting carriage is adapted to be reciprocated. A tension spring 26, attached at one end to front plate 4 and at the other end to a part of the carriage side-bracket 22, serves to urge the carriage in a forward direction, the position shown in Fig. 1.

In order that the assembly of the slideable carriage and tuning cores may be stopped automatically at predetermined positions of adjustment, the turret 13, previously mentioned, is provided. The turret 13 and its shaft 10 are shown in detail in Figs. 4, 5 and 6. On the shaft, between a pair of nuts 27 and 28 which are threaded on the shaft in spaced relation, is mounted a guide member 29 provided with six equi-angularly spaced grooves 30 which extend in the direction of the shaft. The opposite ends of the guide at 31 and 31' are of reduced diameter to provide bearing surfaces for front and rear end-plates 32 and 33. As shown in Fig. 6, one of the grooves designated 30a is undercut below the others and, unlike the others, extends through the end bearing surfaces 31 and 31' to provide key-ways which are adapted to receive locking keys 34 and 35 formed on the end-plates 32 and 33, respectively, to prevent rotation thereof with respect to the guide member.

Extending between the two end plates 32, 33 and equi-angularly spaced near their peripheries are six lead screws 36A to 36E and 36M which are provided each at its rear end with a reduced bearing portion 37 journaled within a hole 38 formed in the rear end-plate. The lead screws are provided at their forward ends with heads 39A to 39E and 39M, respectively, which extend through and are journaled at their bases within holes

40 formed in the front end-plate. A spring plate 42 also keyed to the guide member 29 at its rear end is clamped at the center between nut 28 and rear end-plate 33. The spring plate is provided with six radially-extending fingers 43 which coact each with the bearing portion 37 of a lead screw to spring-press the same in a forward direction. The screw heads 39 are provided with radial slots 44 adapted to be engaged by a manually-operated key, later to be described, and all the screw heads are of the same length except the one designated 39M utilized to effect manual tuning which is made somewhat longer.

Threaded on the lead screws are stop-nuts, designated 45A to 45E and 45M to correspond with their respective lead screws. In order to permit of individual axial adjustment of the stop-nuts, which have the configuration shown in Fig. 6, their reduced portions 46 are disposed within 20 their respective grooves 30 and 30a in guide member 29 so that upon rotation of a lead screw, its stop-nut is restrained from rotation with respect to the lead-screw but is permitted to move axially within its groove. Fitted over the several screws 25 at the rear thereof are tubular fibre spacers 47 which are adapted to limit the range of stop-nut adjustment. The front plate 32 is also keyed to the guide member and is provided around its periphery with six equi-angularly spaced projections 30 which are radially-aligned with the lead screws and their stop-nuts. These front-plate projections are designated 48A to 48E and 48M and are of the same length except the one designated 48M which is made longer for a purpose 35 hereinafter to be explained. In assembling the turret, the front plate 32 is keyed in position on the turret shaft so that the longer projection 48M is disposed diametrically opposite the longer screw head 39M, and the remaining projections 48A to 40 48E are similarly disposed diametrically opposite their correspondingly numbered screw heads 39A to 39E.

During a cycle of operation, the turret assembly as a unit is actuated rearwardly in an axial direction to a limiting position after which it is returned by spring means in the opposite or forward direction to its original position of rest. During this rearward and forward travel of the turret assembly, the linear movement thereof is converted by means later to be described to one of rotation through an angle of 60° which is the angular distance between the six circularly-arranged turret-screws, and stop-nuts. To limit the rearward travel of the turret assembly, a stop member 49 is affixed to shaft 10 at a suitable distance from the rear end thereof. The stop member is in the form of a C-washer fitted into a circular groove 50 in the shaft and therefore keyed thereto, and in coacting with the rear bracket 5 the stop member limits rearward travel of the turret assembly. A felt washer 49' is interposed between C-washer stop 49 and bracket 5 to cushion the rearward thrust of the turret assembly. The forward or return travel of the turret assembly is brought about by a leaf-spring 51 engaging the rear end of the shaft and is limited by the front lock nut 27 coacting with the edge of bushing 11 within which the forward end of the shaft is journaled.

As heretofore mentioned, the turret is rotated or stepped through 60° to its operative position of adjustment during each cycle of operation, and the means for effecting this stepping action will now be described. The frame member 1 is pro-

vided at 52 with a cut-out or slot of the configuration shown in Fig. 1, the slot being disposed in overlying relation with respect to the front end of the turret. The slot, shown in plan in Fig. 1, is shown in Figs. 7A and 7B enlarged to about twice its actual size. The slot is Y-shaped, having a center part 53 which extends in a direction parallel to the turret shaft, a pair of side parts 54 and 55 which emanate rearwardly from part 53, and a pair of substantially rectangular parts 56 and 57 in which the parts 54 and 55 terminate, respectively.

At the beginning of the cycle of operation, assuming the angular turret adjustment shown in Figs. 4 and 5, the turret is in a position of rest and is spring-pressed forwardly by the leaf spring 51. In this position the uppermost projection 48M on the front turret-plate 32 extends vertically upward through the center slot part 53 at the front end thereof as shown in Fig. 7A. The adjacent plate projections 48A at the left and 48E at the right, will then appear underneath the frame 1 in their respective dotted-line positions as shown. During the initial rearward motion of the turret assembly and until projection 48M reaches the position indicated at 48M-1 whereat it coacts with the upper edge 54' of the slot part 54, there is no rotation of the turret. The corresponding positions for the adjacent projections are indicated at 48A-1 and 48E-1. As the turret assembly continues to move rearwardly, the projection 48M is constrained to move along the upper edge 54' until it reaches the position indicated at 48M-2. During this portion of the rearward travel of the turret, the slot edge 54' acts to cam the turret in a clockwise direction through 30°. Simultaneously, the adjacent projection 48A at the left is moved through an arc from position 48A-1 to 48A-2 where it just enters and protrudes through the terminal slot part 57, and the other adjacent projection 48E at the right is moved away from the right-hand terminal slot 56.

Shortly thereafter stop-member 49 on the turret shaft coacts with felt washer 49' and bracket 5 at which time the turret assembly reaches its limit of travel in the rearward direction, and the actuating force for moving the turret is made ineffective. Spring 54 which was flexed during the rearward travel of the turret now acts to urge the turret in a forward direction. The projection 48A at the left now begins to move from its position at 48A-2 in Fig. 7A to the position indicated at 48A-3 in Fig. 7B. Simultaneously the projection 48M moves from its position indicated at 48M-2 in Fig. 7A to the position indicated at 48M-3 in Fig. 7B. At the position 48A-3 for projection 48A, the latter begins to coact with the lower edge 55' of the slot part 55 and during the course of travel of projection 48A from this latter position to the position indicated at 48A-4, the slot edge 55' acts to cam the turret in a clockwise direction through a further 30° rotation. During the final part of forward travel of the turret assembly, the projection 48A will drop towards the front part of the center slot 53 where it comes to rest, replacing the projection 48M which was in the rest position in slot part 53 at the beginning of the cycle (see Fig. 7A). It will be seen, therefore, that during the rearward and forward travels of the turret which are designated T_R and T_F respectively in Figs. 7A and 7B and which constitute a cycle of operation, the turret will have been stepped or rotated through 60° in a clockwise direction.

Since the turret-rotating projections move in a circle about the turret shaft as a center, the portion of the frame surrounding the cam slot, between the terminal parts 56 and 57, is made arcuate as shown at 58 in Fig. 2 in order to accommodate first the arcuate travel of one projection through the cam-slot part 54 and then the arcuate travel of the next projection through the cam slot part 55.

The sole actuating device for the tuning mechanism is a solenoid mechanism, the functions of which are to drive the turret from its forward rest position to its rear limiting position as described above, and to move the tuning-core carriage also from a rest position to a limiting position. The solenoid, shown generally at 60 in Figs. 2 and 8, is supported at the lower end of a bracket 61, below and in parallelism with the turret, and the upper end 62 of the bracket is attached to the underside of the frame 1 at 62' (Figs. 8 and 9).

The solenoid (see Fig. 8) consists of a coil 63 wound on a sleeve 64, a tapered core 65 extending into the sleeve at the left, and an armature or plunger movably mounted within the sleeve at the right. The core is threaded at 67 and a lock-nut 68 screwed thereon is adapted to maintain the core in an axially adjusted position within the coil. The movable armature or plunger on the side facing the core is provided with a conical bore 66' so that when the plunger is actuated to the left it will seat itself on the conical end of core 65. The armature 66 at the right is provided with a reduced portion 69 which is adapted to receive, between a pair of grommets 70, the forked end 71 of a bracket 72. This bracket consists of a center part 73, an arm 74 provided with the above mentioned forked end 71 turned downwardly at right angles to the center part at one end, and an arm 75 provided with a second forked end 76 turned upwardly at right angles to the center part at the other end. The bracket arm 75 is provided with an aperture 77 through which there passes a shaft 78 supported between a pair of ears 79 which extend from the bracket 61 at right angles thereto. A coil spring 80 is disposed between the ear 79 at the left and the bracket arm 75 in order to urge the armature 66 to the right, externally of the solenoid coil, when the solenoid is deenergized. In order to provide true linear motion for the armature 66 and the bracket 72 affixed thereto, there is attached to the center part 73, by spot-welding or otherwise, a member 81 having an apertured upstanding part 82 through which the shaft 78 extends, thereby providing a double suspension on shaft 78 for the armature carrying bracket 72.

The forked end 76 of bracket arm 75 is adapted to engage the turret shaft 10 to the rear of the turret clamping nut 20 (Figs. 4 and 8), and disposed on the shaft between bracket arm 76 and the C-washer stop 49, in the order named, are a felt washer 83, the forked end 84 of a bracket affixed to the carriage side bracket 22, a second felt washer 85 and a metal washer 86 (Figs. 4 and 8). As best seen in Figs. 11 and 12 the carriage side bracket 22 has attached to it at its forward end a bracket 87 having an arm 88 bent at right angles, with the bifurcation 84 above-mentioned formed at the end of said arm.

Upon energization of the solenoid 60, by the closure of a switch 89 (Fig. 1) under the control of a manually-operated member, such as a push-button 90, which may extend through the front panel 91 of the receiver or be carried on the steer-

ing wheel in the case of a receiver installed in an automobile, its armature 66 is pulled in to thereby actuate the forked end 76 of the bracket 72 rearwardly or to the left as viewed in Figs. 4 and 8. This actuation causes the rearward travel of the core carriage 9 by reason of the coaction between said forked end 76 and the forked end 84 of the carriage bracket 87, and causes also the rearward travel of the turret by reason of the coaction between the rearwardly driven forked end 84 and the group of washers 85, 86 and 49. The relative positions of said driving and driven forked arms 76 and 84, respectively, and the turret stop 49, at the beginning of a cycle of operation, are shown in Fig. 8. In Fig. 9 the solenoid armature is shown at the end of its stroke, and the turret assembly and the driven forked arm 84 for the core-carriage are shown in their respective limiting positions. In this state of the mechanism the tuning cores 15 are in their fully entered position with respect to their coils.

In order that the core-carriage may be stopped at a predetermined position corresponding to the angular adjustment of the turret, the carriage side-bracket 22 is provided with a plate member 92 which extends horizontally, underneath the turret and tangentially thereto (Figs. 3, 11 and 12). Affixed to the upper surface of member 92, as by rivets 93, is a stop plate 94, the forward end of which overhangs the forward end of the supporting plate 92. In order to prevent relative shift between the stop plate and its supporting plate, the rear end of the former abuts against a raised protrusion 95 formed in the latter. In a set position of the turret (see Figs. 3 and 8) the lowermost stop nut, 45A in Fig. 3 and 45M in Fig. 8, is the one with which the stop plate 94 coacts and which is effective to stop the core-carriage and tuning element at a predetermined position of adjustment.

From the preceding description it is believed that the operation of the tuning mechanism of the invention will be clear. However, in the way of summarizing, the following brief explanation of a complete cycle of operation will be given. It is assumed that at the beginning of this cycle of operation, the turret is in the angular position shown in Figs. 4, 5 and 8, which is the position to which the turret was set in the previous cycle and in which the stop-nut 45M was effective. To initiate operation of the tuner to effect its adjustment to the next position in the sequence in which the several predetermined stations are adapted to be tuned-in, push-button 90 (or its equivalent) is actuated to close switch 89 for the purpose of energizing solenoid 60. As a result armature 66 is pulled into the solenoid, winding 63 against the action of spring 89, and the solenoid bracket 72 is thereby actuated rearwardly, carrying along with it the core-carriage 9 and the turret 13. The first to move is the core-carriage to bring about the disengagement between stop-plate 94 and the stop-nut 45M. After a short interval, the time that it takes for forked arm 76 to actuate forked arm 84 from its rest position to the position occupied by the stop washer group 49, 86 and 85, the turret begins to move rearwardly and continues to do so until stopped by coaction of stop washer 49 against washer 49'. At this instant the core-carriage is in its most rearward position, whereat the tuning cores are fully entered in their respective coils, and the turret is in its most rearward position. As heretofore explained in connection with Figs.

7A and 7B, the turret is rotated through 30° in a clockwise direction during the course of its rearward travel TR.

With the solenoid deenergized after the carriage and turret have reached their limiting positions, spring 80 causes the return of the armature bracket 12 to its original forward position (Fig. 8), removing thereby the driving force for the turret and core-carriage. The turret is now 5 permitted to move in a forward direction under the action of leaf spring 51 and the carriage is also permitted to move in a forward direction under the action of coil spring 26. Since the turret is caused to move through a shorter distance than the core carriage, it will arrive at its forward rest position, after having been rotated through an additional 30° as previously described, slightly ahead of the carriage, so that the turret 10 will have been moved to its next successive position 15 in the sequence to present the stop-nut 45A in the path of forward travel of the carriage stop-plate 94. With the carriage thus returned to its 20 new position whereat it coacts with the stop-nut 45A just brought into position, the cycle of operation 25 is completed.

In order to effect manual tuning of the receiver, when desired, and also to make the initial individual adjustments of the several stop-nuts, there is provided a manual tuning and adjusting device 100, shown generally in Figs. 1 and 3, for example, and in detail in Fig. 13. The device 30 100 extends through an aperture 101 formed within front plate member 4 and is axially aligned with the lowermost lead screw and screw head 35 of the turret assembly. Within a bushing 102 which is retained within aperture 101 by a forced fit, there is slidably mounted a shaft 103 having a main body portion 104 and a reduced portion 105, which is adapted to extend through an aperture 106 in the front panel 91 of the receiver and to have mounted at its outer end a manual tuning 40 knob 107. Spaced forwardly of the main body of the shaft is a circular groove 108 which is adapted to receive a C-washer 109, and between 45 a shoulder 110 at the right of the main shaft body 104 and the C-washer 109 are disposed a washer 111, a coil spring 112, and a second washer 113. The washer 111 is urged by spring 112 against a shoulder 114 formed on the inner surface of the bushing 102 so that by depressing shaft 103 by means of knob 107 the shaft is urged rearwardly against the action of the spring and upon the release of the tuning knob the spring 112 tends to return the shaft to its normal forward position.

At the other side of shaft 103 there is provided a reduced portion 115 which is adapted to receive the apertured end of a hollow housing 116 provided with two diametrically opposed slots 117 60 within which the sides 118 of a flat key 119 is adapted to be slidably fitted. A coil spring 120 is disposed within the housing between the base portion 121 of the key and the shaft supported end of the housing to permit relative movement of the key with respect to the shaft. This relative movement of the key is necessary when the turret assembly is being rotated to its manual tuning position shown in Fig. 8. Since the key is in the path of the longer screw head 39M, it is necessary that the key be free to move in an axial direction when urged to do so by the screw head until the latter finally comes to rest when the key will eventually drop into a pair of aligned screw head grooves 44 due to the action of coil 65 spring 120.

The turret is shown in Fig. 8 in the manual tuning position, in which position as heretofore stated the key 119 is engaged with the longer screw head 39M so that depression of tuning knob 107 is unnecessary for manual tuning. Rotation of shaft 103 by means of the tuning knob effects axial movement of the stop-nut 45M on its lead screw 36M and the concomitant travel of the core carriage which is spring-pressed in a forward direction whereat the stop-plate 94 contacts with stop-nut 45M.

As heretofore stated the longer projection 48M on the turret front plate 32 is disposed diametrically opposite the longer screw head 39M so that in the manual tuning position shown in Fig. 8, the projection 48M extends through the cam-slot 52 and in a position to close a switch 125 mounted on the frame 1 above the turret assembly. This switch closes a circuit for a dial light 126 (see Fig. 1) located behind an indicator plate 127 in the front panel 91 to visually indicate that the tuner is set for manual operation.

For the purpose of initially setting-up the various stations to which it is desired that the tuner be automatically adjusted, the push-button 90 is actuated to effect rotation of the turret to any angular position. In this turret position the manual tuning shaft 103 is pressed in against the action of springs 112 and 120 to force key 119 to engage the screw head aligned therewith. The shaft in the depressed position is now rotated by knob 107 to cause the corresponding stop-nut to be moved in an axial direction, which in turn causes the core carriage to move. The tuning knob is thus manipulated until the desired station is received. The knob is then released, and thereafter when the turret is again rotated to the above angular position the receiver will be tuned-in automatically to said selected station. The same procedure as above is followed for the different angular turret positions, except that for which manual tuning is employed, so that in subsequent actuations of the push-button 90, the various selected stations will be tuned-in automatically and in a predetermined sequence.

It will be noted from Fig. 4 that the lead screw 36M which serves to effect manual tuning is shown as having a greater pitched screw-thread than the other lead screws 36A to E used to effect automatic tuning. This is to provide more rapid travel of the carriage-coacting stop-member 45M for manual tuning and a relatively slow or micrometer adjustment of the stop-nuts 45A to E for initially setting up the stop positions to which the tuner is to be automatically actuated.

A pointer mechanism for indicating the tuning core position, or the frequency adjustment of the receiver, is shown generally at 130 in Fig. 1. The mechanism is supported on a bracket 131 attached to the under side of the frame 1. Since this mechanism does not form a part of the present invention, further description thereof will not be given except to state that actuation thereof is accomplished by means of an upstanding pin 132 mounted on the core carriage and that the linkage employed in the mechanism for actuating the pivoted pointer arm 133 is such that the pointer 134 at the end of said arm extending through an elongated slot 135 in the front panel 91 of the receiver is caused to travel linearly within said slot in response to linear travel of the core carriage over its range. In other words, the pointer mechanism functions to translate the linear movement of the carriage or tuning element in one direction to a similar movement of the pointer

but in a direction which is at right angles to the first mentioned direction.

While I have shown and described a preferred embodiment of my invention, it will be understood that various modifications and changes will occur to those skilled in the art without departing from the spirit and scope of this invention. I therefore contemplate by the appended claims to cover any such modifications as fall within the true spirit and scope of my invention.

What I claim is:

1. The combination, in radio apparatus, of an adjustable tuning element, a rectilinearly movable carrier for said tuning element, a cylindrical turret provided with a plurality of circumferentially arranged stops, individually adjustable in an axial direction each to a position which determines a particular setting to which the tuning element is actuatable, said turret being capable of both axial and rotary movements, means operable to move the tuning element carrier to a limiting position and simultaneously to move the turret in an axial direction, means including a cam slot coacting with the turret to convert the axial movement thereof to rotary movement whereupon in response to actuations of the carrier-moving means the turret is rotated step-by-step to successive positions at each of which a stop corresponding to the turret position is made effective, and means operable to move the tuning element carrier from its limiting position to one whereat it coacts with the then effective stop as determined by the turret position whereby the tuning element is adjusted to the setting corresponding to said stop.
2. The combination, in radio apparatus, of an adjustable tuning element, a movable carrier for said tuning element, a turret provided with a plurality of stops, individually adjustable each to a position which determines a particular setting to which the tuning element is actuatable, said turret being capable of both axial and rotary movements, means operable to move the tuning element carrier to a limiting position and simultaneously to move the turret in an axial direction, a fixed member spaced from the turret and having a cam slot formed therein, means carried by the turret and coacting with the cam slot to convert the axial movement of the turret to rotary movement whereupon in response to actuations of the carrier-moving means the turret is rotated step-by-step to successive positions at each of which a stop corresponding to the turret position is made effective, and means operable to move the tuning element carrier from its limiting position to one whereat it coacts with the then effective stop as determined by the turret position whereby the tuning element is adjusted to the setting corresponding to said stop.
3. The combination defined in claim 2 wherein the turret is provided with a disk having a plurality of equally-spaced projections equal to the number of turret stops disposed around its periphery, said projections constituting the means which coact with the cam slot, and wherein the cam slot is of such configuration that concomitant with axial movement of the turret, coaction of a turret projection within the cam slot causes rotation of the turret through an angle equal to the angular spacing of the projections.
4. The combination defined in claim 2 wherein the cam slot is Y-shaped and is disposed with its center portion extending in the direction of axial movement of the turret and with its arm portions converging forwardly, and wherein the turret is

provided with a disk having a plurality of equally-spaced projections equal to the number of turret stops disposed around its periphery, the arrangement being such that in a state of rest, at which time the turret is in its most forward position, one of the disk projections extends into the center slot portion at its forward end, and during rearward axial movement of the turret said projection is caused to enter from said center portion into one of the arm portions to cause partial rotation of the turret, and during the return axial movement of the turret to its state of rest the next adjacent projection is caused to enter first into the other arm portion and then into the center slot portion to complete the rotation of the turret, the total rotation of the turret being equal to the angular spacing of the turret-disk projections.

5. The combination defined in claim 2 wherein the cam slot is formed with a linear portion which extends in a direction parallel to the direction of axial movement of the turret and with a pair of forwardly converging portions which communicate with the linear portion at one end thereof, and wherein the turret is provided with a disk having a plurality of equally-spaced projections equal to the number of turret stops disposed around its periphery, the arrangement being such that in a state of rest, at which time the turret is in its most forward position, one of the disk projections extends into the linear slot portion at its forward end, and during rearward axial movement of the turret said projection is caused to enter into one of the converging slot portions wherein an edge thereof in coacting with said projection serves to impart rotation to the turret through a part of its normal rotation, and during the return axial movement of the turret to its state of rest the next adjacent projection is caused to enter into the other converging slot portion wherein an edge of the latter portion in coacting with said next projection serves to impart rotation to the turret through the remaining part of its normal rotation, the angular spacing of the disk projections constituting the normal rotation of the turret.

6. The combination, in radio apparatus, of an adjustable tuning element, a supporting structure, a carrier for said tuning element mounted for linear movement on said supporting structure, a multi-position rotatable turret the angular position of which determines the particular setting to which the tuning element is actuatable, a shaft on which the turret is mounted arranged for axial and rotary movement, a stop member on the shaft cooperatively engageable with said supporting structure for limiting the axial movement of the shaft and turret, a bracket affixed to the carrier mounted for causing linear movement of the turret shaft, actuating mechanism for the carrier and turret having a reciprocable member also mounted on the turret shaft, said reciprocable member, upon operation of the actuating mechanism to drive said member to its limiting position, arranged to actuate the tuning element carrier and turret shaft to their respective limiting positions, means for effecting individual travel of the reciprocable member, tuning element carrier and turret shaft away from their respective limiting positions, and means cooperating with the turret for imparting rotary motion thereto during axial travel of the turret shaft in both directions, the return of the tuning element carrier to its new position of adjustment, as determined by the rotary adjustment of the tur-

ret, occurring after the return of the turret shaft to its normal axial position.

7. The combination, in radio apparatus, of an adjustable tuning element, a supporting structure, a carrier for said tuning element mounted for linear movement on said supporting structure, a turret provided with a plurality of stops, individually adjustable each to a position which determines a particular setting to which the tuning element is actuatable, a shaft on which the turret is mounted arranged for axial and rotary movement, a stop member on the shaft cooperatively engageable with said supporting structure for limiting the axial movement of the shaft and turret, a bracket affixed to the carrier mounted for causing linear movement of the turret shaft, actuating mechanism for the carrier and turret having a reciprocable member also mounted on the turret shaft, said reciprocable member, upon operation of the actuating mechanism, arranged to travel in a direction from its normal position to a limiting position against the action of a spring which, upon the actuating mechanism becoming inoperative, causes the return of said member in the opposite direction to said normal position, said reciprocable member during its travel in said first direction acting first to engage the carrier bracket to move the carrier against the action of the spring to its limit of travel and later to engage the stop member on the turret shaft to move the latter from its normal position to a limiting position against the action of a spring, the return of the turret shaft by its spring to its normal position occurring during the first part of the return travel of the reciprocable member, and means cooperating with the turret for imparting rotary motion thereto during the axial travel of the turret shaft in both directions, the return of the tuning element carrier by its spring to its new position of adjustment, as determined by the rotary adjustment of the turret, occurring after the return of the turret shaft to its normal axial position.

8. The combination, in radio apparatus, of an adjustable tuning element, a reciprocable carrier for said tuning element, a multi-position rotatable turret provided with a plurality of stops, one for each turret position, said stops being individually adjustable axially of the turret each to a position which determines a particular setting to which the tuning element is actuatable, actuating mechanism operable upon each actuation to withdraw the carrier from a previously adjusted setting and to impart linear motion to the turret, means including a cam slot for converting the linear motion of the turret to rotary motion whereby the turret is stepped to a position whereat the corresponding stop is made effective, and means operable to return the tuning element carrier to abut against the said effective stop whereby the tuning element is adjusted to the setting corresponding to said stop.

9. The combination defined in claim 8 wherein the turret is provided with a plurality of equi-angularly arranged projections, one for each turret position, and said projections cooperating successively with the cam slot to effect the step-by-step rotation of the turret.

10. The combination, in radio apparatus, of an adjustable tuning element, a movable carrier for said tuning element, a turret provided with a plurality of equi-angularly arranged stops, individually adjustable axially each to a position which determines a particular setting to which the tuning element is actuatable, said turret being

capable of both axial and rotary movements, means operable to move the tuning-element carrier to a limiting position and simultaneously to move the turret in an axial direction, a fixed member spaced from the turret and having a cam slot formed therein, a plurality of equi-angularly arranged projections carried by the turret, said projections being radially aligned each with one of the tuning element stops and adapted to coact individually with the cam slot to convert the axial movement of the turret to rotary movement, whereupon in response to actuations of the carrier-moving means the turret is rotated step-by-step to successive positions at each of which the stop corresponding to the new turret position is made effective, and means operable to move the tuning element carrier from its limiting position to one whereat it coacts with the then effective stop whereby the tuning element is adjusted to the setting corresponding to said stop.

11. The combination defined in claim 10 wherein the turret has a predetermined angular position at which the tuning element is actuatable by manual means, and a switch is provided in circuit with a dial light which serves as a visual indicator for said manual tuning position, said dial-light circuit-switch adapted to be closed by one of the turret projections.

12. The combination defined in claim 10 wherein one of the turret projections is longer than the others and the turret has a predetermined angular position at which the tuning element is actuatable by manual means, and a switch in circuit with a dial light serving as a visual indicator for said manual tuning position operable by said longer projection to close said dial-light circuit-switch.

13. The combination defined in claim 10 wherein the tuning-element stops are threaded each on a lead-screw provided with a screw-head at one end, and the stop which is effective for any turret position is diametrically opposite to the projection which for that turret position is located within the cam slot, and a device for adjusting

the respective axial positions of said stops, said device comprising a manually-operable shaft which for any adjusted position of the turret is axially aligned with the lead-screw the stop of which is effective to position the tuning element, and a key at the end of said shaft normally spaced from the screw-head of the aligned lead-screw and adapted to interlock therewith when the shaft is pushed in and to rotate the lead-screw when the shaft is rotated.

14. The combination defined in claim 10 wherein the tuning-element stops are threaded each on a lead-screw having a screw-head at one end, one of said lead screws having a greater pitched thread than the others to provide a more rapid travel of the associated stop, a device for adjusting the respective axial positions of the several tuning-element stops comprising a manually-operable shaft, the angular setting of the turret at which said greater pitched lead-screw and manually-operable shaft are aligned serving as the manual tuning position of the apparatus, the screw-head at the end of said greater pitched lead-screw being longer than the others and just long enough to interlock with the key in the normal shaft position, the radial turret projection which cooperates with the cam slot at the manual tuning setting of the turret being longer than the others and a switch located above the cam slot adapted to be closed by said longer turret projection, said switch being included in a circuit for the dial light which serves as a visual indicator for said manual tuning setting.

ALBERT BLAIN.
